(57) **CLAIM**

The ornamental design for a hatch tray, as shown and described.

DESCRIPTION

FIG. 1 is a bottom perspective view of a hatch tray showing my new design;

FIG. 2 is an enlarged fragmentary bottom perspective view of the hatch tray shown in FIG. 1;

FIG. 3 is a bottom plan view thereof;

FIG. 4 is a left view thereof;

FIG. 5 is a right view thereof;

FIG. 6 is a front view thereof;

FIG. 7 is a back view thereof;

FIG. 8 is a top perspective view of the hatch tray shown in FIG. 1;

FIG. 9 is an enlarged fragmentary top perspective view of the hatch tray shown in FIG. 8;

FIG. 10 is a top plan view thereof;

FIG. 11 is a left view thereof;

FIG. 12 is a right view thereof;

FIG. 13 is a front view thereof; and,

FIG. 14 is a back view thereof.

The broken lines illustrate unclaimed environment and form no part of the claimed design.
